DEVICE FOR POSITIONING A PAIR OF COILS ON THE NECK PORTION OF A CATHODE RAY TUBE

Peter G. Puhak, Seneca Falls, N.Y., assignor to GTE
Sylvania Incorporated, Seneca Falls, N.Y.

Filed Aug. 14, 1974, Ser. No. 497,277

Term of patent 14 years

Int. Cl. D13—03

U.S. Cl. D26—1 D

FIG. 2

FIG. 3

FIG. 1 is a top plan view of a device for positioning a pair of coils on the neck portion of a cathode ray tube showing my new design;

FIG. 2 is a rear perspective view thereof on an enlarged scale; and

FIG. 3 is a front perspective view thereof on an enlarged scale.

The broken lines representing the outline of the cathode ray tube are shown for illustrative purposes only.

I claim:

The ornamental design for a device for positioning a pair of coils on the neck portion of a cathode ray tube, as shown and described.
